CLAIM

The ornamental design for a portable negative pressure wound care appliance, as shown and described.

DESCRIPTION

FIG. 1 is a perspective view of a portable negative pressure wound care appliance showing my new design;

FIG. 2 is a front elevational view thereof;

FIG. 3 is a left side elevational view thereof;

FIG. 4 is a top plan view thereof;

FIG. 5 is a back elevational view thereof;

FIG. 6 is a perspective view thereof; and,

FIG. 7 is a perspective view of the two components of the portable negative pressure wound care appliance as they would be separated after use.
